US0D1101327S

(12) **United States Design Patent** (10) **Patent No.:** **US D1,101,327 S**
(45) **Date of Patent:** **** Nov. 4, 2025**

(54) **DUST SEPARATOR**

- (71) Applicant: **FASTER BETTER EASIER, LLC**,
Orion Township, MI (US)
- (72) Inventor: **Thomas E. Huntley**, Auburn Hills, MI
(US)
- (73) Assignee: **FASTER BETTER EASIER, LLC**,
Orion Township, MI (US)
- (**) Term: **15 Years**
- (21) Appl. No.: **29/962,621**
- (22) Filed: **Sep. 12, 2024**

Related U.S. Application Data

- (60) Division of application No. 29/857,061, filed on Oct. 19, 2022, now Pat. No. Des. 1,048,618, which is a continuation of application No. 17/732,037, filed on Apr. 28, 2022, which is a continuation-in-part of application No. 17/088,047, filed on Nov. 3, 2020, which is a continuation of application No. 15/465,051, filed on Mar. 21, 2017, now Pat. No. 10,857,550.
- (51) **LOC (15) Cl.** **15-05**
- (52) **U.S. Cl.**
- USPC **D32/31**
- CPC **B04C 1/00** (2013.01); **B01D 45/08** (2013.01); **B04C 5/081** (2013.01); **B04C 5/185** (2013.01); **A47L 9/16** (2013.01); **A47L 9/1608** (2013.01); **A47L 9/165** (2013.01); **B01D 45/00** (2013.01); **B01D 45/12** (2013.01); **B01D 45/16** (2013.01); **B04C 5/103** (2013.01)

(57) **CLAIM**

The ornamental design for a dust separator as shown and described.

DESCRIPTION

FIG. 1 is a front, side, and top perspective view of a dust separator according to an embodiment;

FIG. 2 is a front perspective view of the dust separator of FIG. 1;

FIG. 3 is a section view of the dust separator taken along section line 3-3 in FIG. 1; and,

FIG. 4 is a bottom view of the dust separator of FIG. 1. The broken lines are for illustrative purposes only and form no part of the claimed design.

1 Claim, 4 Drawing Sheets
